UNITED STATES PATENT OFFICE.

DAVID E. BURNS, OF GRAND RAPIDS, MICHIGAN, ASSIGNOR OF ONE-HALF TO HAROLD J. MCKINLEY, OF GRAND RAPIDS, MICHIGAN.

ROAD SCRAPER.

Application filed April 3, 1922. Serial No. 549,080.

To all whom it may concern:

Be it known that I, DAVID E. BURNS, a citizen of the United States of America, residing at Grand Rapids, in the county of 5 Kent and State of Michigan, have invented certain new and useful Improvements in Road Scrapers; and I do hereby declare the following to be a full, clear, and exact description of the invention, such as will enable others skilled in the art to which it 10 pertains to make and use the same.

This invention relates to improvements in road scrapers and more particularly to such scrapers adapted to be attached to the 15 frame of a motor vehicle, preferably a motor truck, and its object is to provide a scraper which may be quickly attached and readily adjusted to any ordinary type of motor truck, which may be quickly removed when 20 not in use, and which will effectively and smoothly scrape the surface of the road over which the vehicle passes.

The scraper blade is yieldably held against the road surface when in operative position 25 and the device is provided with means by which the pressure of the blade upon the road surface may be graduated and this means is also adapted to raise the blade entirely from the road surface when so desired. Means for raising and lowering the 30 scraper blade and also for adjusting the blade either parallel or angularly relative to the road surface is also provided, and the device has various other new and useful features of construction and arrangement which are hereinafter more fully described and particularly pointed out in the claims, reference being had to the accompanying drawings, in which:

40 Fig. 1 is a side elevation of a motor truck showing the road scraper embodying this invention attached thereto in operative position.

Fig. 2 is a plan view, diagrammatic in nature, of the chassis of the truck showing the road scraper applied thereto.

Fig. 3 is a fragmentary elevation, partly in section, of the adjustable shaft used for operating the pressure controlling means.

50 Fig. 4 is a fragmentary section of the bracket which attaches the scraper to the

frame of the vehicle showing the connecting device used for this purpose.

Fig. 5 is a front elevation of the scraper also showing portions of the frame of the 55 vehicle.

Fig. 6 is an enlarged perspective view of one of the shaft supporting arms and the adjustable bearings mounted thereon.

Fig. 7 is an elevation of a portion of the 60 scraper blade and the shaft on which it is mounted, showing details of the pressure spring.

Fig. 8 illustrates a modified form of pressure spring.

Fig. 9 is a transverse sectional elevation on the line 9—9 of Fig. 5.

Fig. 10 is an enlarged transverse section through the rock shaft and sleeve showing the pressure spring attached thereto.

Fig. 11 is an elevation, partly in section and with parts broken away, showing the pressure controlling means, and,

Fig. 12 is a longitudinal sectional elevation on the line 12—12 of Fig. 11.

Like reference numbers describe like parts in all of the figures.

1 is the frame of the motor vehicle, which has the usual wheels 2 and a driver's seat 3. 4 is the hanger board from which the scraper is suspended and the hanger board is attached to the under side of the frame members 1 by brackets 5. These brackets are permanently fixed to the hanger board and extend beneath the lower surface of the frame members 1, these frame members preferably being of channel construction, and clamps 6 are provided which embrace both the brackets 5 and a portion of the frame 1, and bind them together by friction attained through 90 the screws 7.

A plurality of arms 8 are attached to the under surface of the hanger board 4 and extend downward therefrom, and each arm has mounted thereon a vertically movable bearing block 9, each of which is provided with a clamping screw 10 threaded in the block and engaging the arm 8. A rock shaft 11, preferably of tubular construction, extends longitudinally beneath the hanger board being journaled in the bearing blocks 9. A plurality of sleeves 12 are located upon

the rock shaft 11, each of said sleeves being provided with clamping screws 13 threaded in the sleeves and engaging the rock shaft, and a pressure spring 14 is coiled about each sleeve, one end of the spring being attached to the sleeve, preferably by being bent inward as at 15, and inserted into a hole in the sleeve, and the other end of the spring extends downward and rearward and is attached to the scraper blade 16 by any suitable fastening means such as U bolts 17 similar to those illustrated.

The scraper blade attached to the rock shaft as above described is pressed against the road surface by means of the springs 14 when the rock shaft 11 is rotated in a direction to tighten the springs. The following described means is employed to rotate the rock shaft 11. A worm gear segment 18 is attached to the rock shaft 11, and a worm 19 located adjacent the upper periphery of the worm gear meshes therewith being fixed to a shaft 20 which is journaled in bearings 21 fixed to an arm 22, the said arm having a hub 23 which surrounds the rock shaft 11 and a collar 24 fixed to the rock shaft retains the hub 23 in its position adjacent the hub of the worm gear 18 and thus insures the proper location of the arm 22 to retain the worm 19 in mesh with the worm gear. The forks 25 extend upward from the arm 22 embracing the hanger board 4 and retain the arm 22 in upright position. The forks will not permit rotation of the arm 22, but they will admit the vertical movement of the rock shaft relative to the hanger board.

A bracket 26 is attached to the frame 1 of the vehicle near the driver's seat and a vertical shaft 27 rotatably mounted in this bracket carries a hand wheel 28 at its upper end, and a bevel gear 29 at its lower end. An extensible shaft comprising the members 30 and 31 and having the universal joints 32 and 33 at its respective ends extends between the shaft 20 on which the worm is mounted and bracket 26 in which the universal joint 33 is journaled, and a bevel gear 34 meshing with the bevel gear 29 transmits the movement of the shaft 27 to the worm 19. The member 30 of the extensible shaft telescopes within the member 31, the member 31 being provided with a plurality of holes through one of which the cotter pin 35 is inserted, the pin also passing through a hole in the member 30 to connect the two members.

The scraper as a unit assembly may be easily fastened to any ordinary motor truck by placing it beneath the frame of the truck and applying the clamps 6 to attach the bracket 5 to the frame and then attaching the bracket 26 in a position convenient to the driver's seat. By virtue of the universal joints 32 and 33 and the extensible feature 65 of the shaft connecting them, the location

of the bracket 26 relative to the scraper assembly may be varied within reasonable limits and yet be made to fit and function properly. The device is installed so that the scraper blade assumes an angle relative to the longitudinal axis of the vehicle and after it has been properly installed the scraper blade 16 is brought into contact with the road surface by rotation of the hand wheel 28 and through its various connecting members rotates the rock shaft 11 and increases the tension of the pressure spring 14 whereby the pressure of the blade against the road surface may be varied at will and when adjusted it will remain in this position because of the irreversible quality of the worm and worm gear connection. The tension of each individual spring 14 may be regulated by rotating the sleeve 12 to which it is connected upon the rock shaft 11 and then clamping the sleeve to the shaft by the set screws 13. If it is desired to operate the truck for a short time without using the scraper blade, the rock shaft may be rotated by means of the hand wheel to raise the scraper blade as illustrated by dotted lines in Fig. 9. It is also easy to remove the scraper assembly by detaching the clamps 6 and disconnecting the extensible shaft members 30 and 31 and thereby relieving the vehicle of the weight and encumbrance of the device when it is not in use.

It is often desirable to have the scraper blade elevated more at one end than at the other, and to obtain this adjustment the vertically movable bearing blocks 9 may be adjusted to the desired position upon the arms 8 and this adjustable feature also enables the blade to be adjusted to the proper height to fit vehicles of different dimensions. When the rock shaft 11 is vertically adjusted by moving the bearing blocks 9 on the arms 8, the worm 19 and worm gear segment 18 always remain in proper relation and the forks 25 slide up or down upon the hanger board 4.

The modified pressure spring construction illustrated in Fig. 8 contemplates the necessity of increasing the spring pressure and utilizes a double spring 14^a in place of the single spring before described, this spring 14^a having a loop 14^b at its middle portion which is attached to the scraper blade 16 and its respective ends each extend upward and are coiled about a sleeve 12^a which is fixed to the rock shaft 11 similar to the sleeves 12. The pressure springs are preferably coiled about the sleeves in the manner shown, that is one end before attached to the scraper blade, the spring 12^a thence extends diagonally upward and forward and thence is coiled from front to rear over and about the sleeve.

I claim:

1. A road scraper, comprising a scraper

- blade, a shaft above the scraper blade, a plurality of springs, each coiled about said shaft and having one end adjustably fastened to the shaft and the other end fastened to the scraper blade, means for rotatably mounting the shaft on a vehicle and manually operable means for turning the shaft. 5 hanger board, a scraper blade attached to the rock shaft, a worm gear segment attached to the rock shaft, a worm meshing with said worm gear segment and journalled in a bracket connected to the hanger board, and means for rotating said worm for the purpose described. 70
2. A road scraper comprising a scraper blade, a rock shaft, a plurality of springs, each coiled about said rock shaft and having one end adjustably attached to the rock shaft and the other end attached to the scraper blade, means for mounting the rock shaft on a vehicle and means for rotating the rock shaft. 10 9. A road scraper comprising a hanger board, means for attaching the hanger board to the frame of a vehicle, a rock shaft mounted on the hanger board, a scraper blade mounted on the rock shaft, a worm gear segment fixed to the rock shaft, a worm meshing with said segment and journalled in a bracket connected to the hanger board, 75 80
- 20 a longitudinally extensible shaft connected by a universal joint to said worm, a bracket fixed to the frame of the motor vehicle, a manually rotatable shaft journalled in said bracket, a bevel gear on said shaft, and a second bevel gear meshing with the first bevel gear and connected by a universal joint to said extensible shaft substantially as and for the purpose described. 85
- 25 3. A road scraper comprising a scraper blade, a shaft, a plurality of sleeves rotatably adjustable upon said shaft, a spring coiled about each sleeve and having one end attached to the sleeve and the other end attached to the scraper blade means for rotatably mounting the shaft on a vehicle and means for manually turning the shaft to raise or lower the scraper blade. 90
- 30 4. A road scraper comprising a scraper blade, a rock shaft, a plurality of sleeves rotatably adjustable upon said rock shaft, a spring coiled about each sleeve having one end attached to the sleeve and the other end attached to the scraper blade, means for mounting the rock shaft on a vehicle, and means for rotating the rock shaft. 95
- 35 5. A road scraper comprising a scraper blade, a shaft above the scraper blade, means for mounting the shaft on a vehicle, and a plurality of springs each having one end attached to the scraper blade and thence extending upwardly and in front of the shaft and coiled about the shaft and having its other end fastened to the shaft. 100
- 40 6. A road scraper comprising a scraper blade, a shaft above the scraper blade, means for mounting the shaft on a vehicle, a plurality of sleeves rotatably adjustable upon the shaft, a plurality of springs each having one end attached to the scraper blade and thence extending upward and in front of a respective sleeve and thence coiled about the sleeve and attached thereto. 105
- 45 7. In a road scraper, a motor vehicle having a chassis frame including parallel side members of channel formation, brackets located one under each side member having ends located under and against the under sides of the lower flanges of said frame members, clamps engaging said flanges and the ends of the brackets to adjustably connect the brackets to said lower flanges of the side members, a hanger board permanently connected to the lower sides of the brackets, and a scraper blade carried by and below the hanger board. 110
- 50 8. A road scraper comprising a hanger board, means for attaching the hanger board to a vehicle, a rock shaft mounted on the 115
- 55 60 65 70 75 80 85 90 95 100 105 110 115 120 125 130

shaft, a plurality of sleeves rotatably adjustable on said rock shaft, a spring coiled about each sleeve and having one end attached to the sleeve and the other end attached to the scraper blade.

13. A road scraper comprising a hanger board, means for detachably connecting the hanger board to the frame of a vehicle, a plurality of arms depending from said hanger board, a vertically adjustable bearing block on each arm, a rock shaft journalled in said bearing block, a scraper blade beneath the rock shaft, a plurality of rotatably adjustable sleeves on said rock shaft, a spring coiled about each sleeve and having one end attached to the sleeve and the other end at-

tached to the scraper blade, a worm gear segment fixed to the rock shaft, a bifurcated arm embracing the hanger board and rotatably connected to the rock shaft, a worm journalled in the arm and meshing with the worm gear segment, a longitudinally extensible shaft connected by a universal joint to the worm, a bracket fastened to the frame of the vehicle, a manually rotatable shaft journalled in the bracket, a bevel gear on the shaft, a second bevel-gear meshing with the first bevel gear and connected by a universal joint to the said extensible shaft.

In testimony whereof I affix my signature. 30

DAVID E. BURNS.
